(57) **CLAIM**

The ornamental design for a display panel with transitional
graphical user interface, as shown and described.

DESCRIPTION

The patent or application file contains at least one drawing
executed in color. Copies of this patent or patent application
publication with color drawing(s) will be provided by the
Office upon request and payment of the necessary fee.

FIG. 1 is a first image of a display panel with transitional
graphical user interface showing our new design; and,
FIG. 2 is a second image thereof.

The appearance of the transitional image sequentially transi-
tions between the images shown in FIGS. 1 and 2. The
process or period in which one image transitions to another
image forms no part of the claimed design.

The dash-dash broken lines depict portions of the display
panel with transitional graphical user interface and form no
part of the claimed design. The dot-dash broken lines define
the bounds of the claimed design and form no part thereof.
